RENEWABLE FACE HAMMER
 Donald E. Small, 522 W. Ave. J-9,
 Lancaster, Calif. 93534
 Filed May 24, 1965, Ser. No. 458,309
 1 Claim. (Cl. 145—36)

This invention relates to hammers and while it is primarily concerned with hand hammers having a head and handle, it is also applicable to other percussive tools such as, for example, presses and the like which may not be equipped with shafts and/or handles. The expression "hammer" is therefore used herein in a general sense to include all kinds of percussive tools.

My invention is primarily concerned with hammers which have a renewable striking face portion being made from soft metallics such as, lead, brass, copper and various compositions of these materials.

One of the objects of the present invention is to provide improvement in such hammers whereby the possibility of a renewable striking face becoming loosened during working will be eliminated.

According to the present invention, I provide a hammer of the kind herein before referred to, a head portion consisting of a relatively hard material (e.g. a metal such as steel) and one or more renewable face portions of a soft nonferrous metal, each face portion having an axially projecting hollow stem which is an integral part of the face portion. In the sockets of the hammer head there is provided a conic section or angular boss which when engaged with the extended hollow stem of the face portion and pressure is applied by a vise or press, the hollow stem will flare out filling the circular recess in the inner wall of the hammer head socket. When it is thus seated, the shoulder of the striking face portion will seat on the face portion of the hammer head, providing a positive locking means, as the flared portion is larger than the entrance portion of the hammer head socket.

A further aspect of the present invention is, I have provided a plurality of dividers located at the base of the hammer head socket. The main object of these dividers is to upset the flared part of the hollow stem of the face portion which is seated in the circular recess of the hammer head so that when hammer head is fixed in a vise the worn face portion may easily be extracted by turning it in either direction.

Certain embodiments of the invention are described herein after, by way of example, and are illustrated in the accompanying drawings wherein:

FIGURE I is a view of a hammer head with two striking faces which herein after will be referred to as renewable tips or tip, one being shown removed.

FIGURE II is a view of a renewable tip with a striking face, this view is to clearly show the notch in the projected hollow stem which is an integral part of the renewable tip. There is a plurality of notches around the periphery of the end of the hollow stem which, when in contact with socket, are in alignment with the plurality of dividers in the hammer head socket.

FIGURE III is a fragmentary section of the hammer head showing construction of the socket.

FIGURE IV shows cutaway section of renewable tip.

FIGURE V is a cutaway section of the hammer head socket.

FIGURE VI is a cutaway section of a renewable tip partially engaged in the hammer head socket.

Referring to the accompanying drawings FIG. I illustrates the head of a hammer and it will be seen that it comprises a head portion 17 made of a suitable steel and provided with an opening 22 extending there through in which is fixed the end of the handle or shaft and each end

2

5 of the hammer head portion 17 is provided with a renewable tip 11, each tip 11 comprising a striking face 10 and axially projected hollow stem 12 with notch 13, hollow stem 12 is of reduced diameter which provides a shoulder 14 this shoulder 14 being seen more clearly in FIG. II and its function and purpose being referred to more particularly herein after. The notch 13 on hollow stem 12 is in plurality and is provided to facilitate easy extraction of worn tip, a further object of notch 13 is to prevent any possibility of radial movement of tip 11 when striking at an angle.

10 As shown more clearly in FIG. III the ends of hammer head 17 are provided with a circular recess or socket 19 surrounding an angular boss or conic section 16 of the recess or socket 19, recess or socket 19 is dimensioned to receive the stem 12 of tip 11 also shoulder 14 of tip 11 when seated rests on face 15 of hammer head 17. The wall of socket 19 is extended straight to the angular boss or conic section 16 thence turning to an abrupt angle outward to the base of the angular boss on conic section 16 where they intersect as shown on cutaway section FIG. V and FIG. VI.

15 FIG. III is a fragmentary section of hammer head 17 showing construction of inner wall of recess or socket 19 angular boss or conic section 16 and divider 18. When shoulder 14 of tip 11 is seated on face 15 of hammer head 17 the notch 13 will be in mesh with divider 18.

20 FIG. IV is a cutaway section of renewable tip 11. When hollow stem 12 of tip 11 is placed by hand into the straight wall portion of socket 19, FIG. V, hollow stem 12 will be free to turn in socket 19 to locate notch 13 relative to divider 18 in socket 19 as shown more clearly in FIG. VI. As will be noted hollow stem 12 of tip 11 will rest on angular portion of conic section 16 with notch 13 in alignment with divider 18 in hammer head socket and when hammer head 17 with inserted tip 11 is installed in a vise or press stem 12 will travel down the slope of conic section 16 until seated at the base of socket 19 thus constituting a true lock and/or interlocking means of tip 11 to hammer head 17. Due to complete absence of voids or cavities in socket 19 when hollow stem 12 is firmly seated at the base of socket 19 and shoulder 14 is resting firmly on face 15 of hammer head 17, seat 20 of hollow stem 12, FIG. II and FIG. III, rests firmly on face 21 of conic section 16.

25 I am aware that prior patents show hammers having soft metal faces or tips; also that prior patents show and describe hammers having a socket at each end into which metal tips are secured, in one case by friction alone and in another by a rivet or screw passing through the walls of the socket setting in the shank of the tip. Another patent shows and describes a hammer with sockets having a dove tailed slot through each end into which tips of various forms having dove tailed shanks or place, and made fast by rivets or screws which pass through the walls of the dove tailed slot and into the dove tailed shank of the tip, and many other forms of sockets in the hammer head with various means of securing renewable soft tips. All of said prior art is hereby disclaimed.

30 I believe my invention to be new and unique in that it is simple in construction and when the tip is pressed into the socket, the hollow stem of the tip flares to conform with the configuration of the socket thus there is no radial and/or angular forces to unseat or loosen the tip within the hammer head socket while the hammer is in use. The only means of loosening the tip from the hammer head socket is by placing hammer head in a vise and turning the worn tip in either direction with a pipe wrench. When thus forcing tip either to the right or the left, as mentioned above, the divider or dividers in the base of the socket will upset the thin edge of the hollow stem of the tip, re-

tracting flared material to a semi-normal position so that worn tip is easily extracted from the hammer head. This hammer head socket and face and the renewable tip including shoulder and hollow stem may be used in many forms without departing from the scope of this invention as long as they are used as a locking means herein described.

What I claim is:

A hammer comprising a head portion of relatively hard metal and a renewable striking tip of relatively soft metal and disposed at each end of the head, said head having a socket extending axially inward from each end, each socket being cylindrical and having an annular channel in the innermost portion thereof extending inward of a central face, said channel being of V-shaped configuration with the apex thereof being at the innermost portion, said channel extending radially outward at an angle to the longitudinal axis of said head, a plurality of dividers at the base of said channel having surfaces converging in the direction of said ends, said renewable tip having a stem defined by a central recess circumscribed by a pro-

jecting flange terminating in an annular edge, said flange having a plurality of V-shaped notches which cooperate with said dividers to first preclude rotation of said tip when said stem is forcibly inserted in said socket, with said notches and dividers in alignment, to cause said stem to expand into locking engagement with said channel, and second to assist in removal of said tip by camming action of the surfaces of said notches and dividers.
